CONTAINER FOR ARTISTS' MATERIALS

George K. Gombarts, New York, N. Y.

Application October 6, 1949, Serial No. 119,839

2 Claims. (Cl. 41—4)

1

This invention relates to a box or container for paints and painting materials, such as are employed by artists, art students and others. An object of the invention is to provide a compact container in which paints, brushes, water or other paint-mixing fluid, palettes and possibly other painting instrumentalities may be very conveniently and compactly held, and all within a relatively small container which is easily carried and used, and particularly when painting outdoors or in the field.

More particularly, the invention contemplates a receptacle having a body provided with a tray portion in which the paints are contained, said tray also being provided with a section for receiving brushes. Located within the body of the container is a water chamber or tank provided at one end with a pouring-opening normally closed by a screw-on cap or other closure, said pouring-opening being in communication with a cup-shaped end pivoted at the end of the body of the receptacle and either pivotal to a position enabling it to act as a water-holding cup during painting activities, or detachable from the body of the receptacle when desired. The opposite end of the body of the receptacle is made hollow to constitute a chamber into which the ends of the brushes may protrude, and attached to the latter end is a foldable carrying handle by which the receptacle is easily transported. One or more pivotal cover members disposed over the top of the tray act, when closed, as closure means for the tray, and these cover members, when opened, not only serve to expose the paints on the tray, but provide inside surfaces which may be used as mixing palettes. To facilitate the holding of the receptacle during painting, and in the manner in which the artist is accustomed to hold a palette, the receptacle is provided on its underside with pivotal loops through which the fingers may be inserted and the receptacle easily and comfortably supported.

With these and other objects to be hereinafter set forth in view, I have devised the particular arrangement of parts described below and pointed out in the claims appended hereto.

In the accompanying drawing, forming a part hereof, and in which an illustrative embodiment of the invention is disclosed, Fig. 1 is a top plan view of the improved box or container in closed position; Fig. 2 is a side elevation, with the water cup in its hanging or dependent position; Fig. 3 is a top plan view of the container in its completely open position ready for use; Fig. 4 is a longitudinal sectional view taken through the con-

2

tainer; Fig. 5 is a sectional view taken on the line 5—5 of Fig. 1 looking in the direction of the arrows; Fig. 6 is a sectional view taken on the line 6—6 of Fig. 3, looking in the direction of the arrows; Fig. 7 is a view of a portion of a bottom of the container, showing how the water cup is detachably and pivotally secured thereto, and Fig. 8 is a perspective view, with parts fragmentarily shown, of the container in its open position.

10 The container or box may be made of metal, of plastic material or of wood, and in the form shown, it includes a body portion 1 of relatively rectangular and elongated form. The body portion includes a bottom wall 2 and the two upper standing side walls 3 and 4. Contained within the body portion 1, and suitably secured in place therein, is a tank or water-chamber 6, which may be used for containing water 7 if the paints contained in the box are water colors, or it might 15 be used for containing other paint-mixing fluids according to the paint contents of the box. The tank or water container 6 is provided with a forward end 8 which protrudes slightly out of one end of the body portion 1, and this protruding end 20 of the tank is provided with a pouring-outlet or neck 9 normally closed by a thread-on or similar closure cap 10. This end of the tank 6, as well as the end of the body portion 1 of the container, is adapted to be covered by a cup-shaped member 11 adapted for use as a water cup and into which 25 some of the fluid 7 from the tank 6 is adapted to be poured, to permit the artist's brushes to be 30 dipped into it for mixing the paints.

This movable cup-shaped member 11 is pivotally as well as detachably connected to the end 35 of the body portion by means of a hinge 12, permitting the cup, when in its open position shown in Figs. 2, 4 and 8, to hang vertically down at the end of the container with its mouth directed 40 upwardly to thereby hold its liquid contents and permit the brushes to be dipped thereinto. The hinge 12 consists of the two loops 13 attached to the cup 11 which loops are adapted to fit about the hinge pins 14 provided on the bottom 2 of the body 1 of the container. It will be apparent that 45 by sliding the cup 11 sidewise or axially of the hinge pins 14, the cup can be detached from the box to facilitate the pouring out of the fluid contents of the cup and permitting it to be readily 50 washed or cleansed before restoring it to its position of pivotal attachment to the body of the container.

Within the container and above the tank 6 is a tray 5, which may be formed by the top or upper wall of the tank 6, and includes the vertical par-

titions 17, dividing a portion of the tray into compartments for the reception of the paints which may be in either block form or contained in the conventional tubes. Forwardly of the partitions is located an area or section designated at 18 for the reception of the brushes. When the cup 11 is in its closed position the end portions of the brushes may extend into the cup 11 as well as project into a hollow end portion 13a provided at the opposite end of the body 1. Said hollow end 13a may be rounded at the bottom as shown, or made of other shape. It is provided at the top with the panel 19 to which is pivotally attached a carrying handle 21. The handle is in the form of a wire loop or bail, and its ends are pivotally received in the loops 20 formed at the end of the container. The extended position of the handle, which is that employed when carrying the container, is shown in Fig. 1, and in its folded position it overlies the panel 19 as shown in Fig. 3, thus decreasing the overall size of the container.

The top of the body portion 1 of the container is closed by a pair of pivoted cover members indicated respectively at 22 and 22a. The inner closure member, indicated at 22, is pivoted at 25 to the upper end of the side wall 4 of the body 1 of the container, and when in its closed position it fits over and closes the top of the tray 5. The second cover member, indicated at 22a is pivoted at 29 to the side wall 3 near the upper edge of the same, and when this cover member 22a is closed it fits over the top of the body 1 and overlies the inner cover member 22. When the two cover members 22 and 23 are in open position, as shown in Figs. 3, 6 and 8, the same lie substantially horizontal and are usable as mixing surfaces or palettes. To confine the paints on these palettes the cover member 22 is provided with the marginal wall 26, while the cover member has the end flanges 27 and front flange 28.

Extending from one of the flanges 27 is a lip 24 of resilient or springy nature, and the same acts as a closure member for the cup 11. The frictional or springy engagement of the lip 24 with the inside surface of the cup 11 serves to retain the cup in its closed position, as shown in Figs. 1 and 5, and at the same time, the cover member 22a is retained in its closed position by this engagement of the parts.

To facilitate the holding or supporting of the container during the painting work, the bottom 2 of the container is provided with spaced loops 15 in which rings 16 are pivotally mounted. The thumb of the user is inserted through the rings 16, and the container is thus supported by the hand in the manner of the conventional artist's palette.

From the foregoing, the operation and uses of the container will be readily understood. In its closed position, the device appears as shown in Fig. 1. When shipped, the container has its handle 21 folded inwardly as in Fig. 3, and the same may then be readily contained in a standard protective box of rectangular formation. To carry the closed container, the handle 21 is extended as shown in Fig. 1. The paints are contained in the compartments defined by the partitions 17 and the brushes in the area 18, with their end portions accommodated in the hollow ends 13a and 11 of the container.

When it is desired to use the device, the cup 11 is swung downwardly on its pivot 12 to vertical position, and by removal of the cap 10 the

required amount of water or other mixing fluid from the tank 6 will be caused to flow into the cup 11. By swinging the cup 11 downwardly, it will be made free of engagement with the lip 24, so that the cover members 22a and 22 may now be swung outwardly from the body 1 to horizontal position to serve as palettes upon which the mixing of the paints may take place. While these covers are shown as flat or plane surfaces, it will be apparent that the same may be formed with depressions or shallow cups in which the various paints may be mixed in the known manner. While painting, the container may be sustained on the hand by the insertion of the thumb through the loops 16. Normally these loops 16 are swung flatwise against the under face of the container.

At the conclusion of the painting operation, the cup 11 may be detached at the hinge 12, as shown in Fig. 7 and the contents spilled out. The cup can then be washed out by the use of water from tank 6, and then restored to the end of the body 1. The covers 22 and 22a are then swung to closed position, and when the cup is swung upwardly and engaged over the lip 24, it will hold the covers closed and be also held in closed position.

By means of the structure described, a compact, easily handled and sturdy container, capable of carrying all of the required artists' materials, excepting the surface used for painting, is provided.

While I have described one embodiment of the invention, it is obvious that the same is not to be restricted thereto, but is broad enough to cover all structures coming within the scope of the annexed claims.

What I claim is:

1. A container for artists' equipment comprising, a box having a body provided with a tray, a liquid-containing tank disposed below the tray, a pivoted end closure for the body consisting of a hingedly attached cup into which liquid can be poured from the tank while the cup remains attached to the body, the pivot for the cup permitting the cup to hang in a suspended, substantially vertical position with its mouth directed upwardly and to hold a quantity of liquid in position for use while painting and while the cup is in such suspended position, the tank having a pouring outlet directed toward the mouth of the cup and from which liquid may be poured directly into the cup while the cup hangs in its suspended position, and covers for the top of the body.

2. A container for artists' equipment comprising, a box having a body provided with a tray for holding artists' colors, a liquid-containing tank in the body beneath the tray, an end closure for the body consisting of a cup, pivotally attached at one of its edges to the body and into which liquid is poured directly from the tank while the cup is held in a suspended position on its pivot, the pivot for the cup permitting the cup to hang in a suspended, substantially vertical position with its mouth directed upwardly and to hold a quantity of liquid while remaining in such suspended position, the tank having a pouring outlet at one end directed toward the mouth of the cup and from which liquid is poured into the cup while the cup remains in its suspended position, covers for the top of the body, a handle at the end of the body remote from the pivoted cup, and finger loops on the body for supporting the

box and its suspended cup while engaged in painting.
